United States Patent Office

Des. 180,884

Patented Aug. 27, 1957

180,884

WOVEN STRUCTURAL MATERIAL

Sawyer M. Pomeroy, Lyndhurst, Ohio, assignor to The
W. S. Tyler Company, Cleveland, Ohio, a corporation
of Ohio

Application September 21, 1955, Serial No. 38,027

Term of patent 14 years

(Cl. D54—2)

Fig. 1

Fig. 2

Fig. 3

Fig. 1 is a plan view showing my design for a woven structural material;

Fig. 2 is a cross-sectional view along the line 2—2 of Fig. 3; and

Fig. 3 is a cross-sectional view along the line 3—3 of Fig. 2.

I claim:

The ornamental design for a woven structural material, substantially as shown.
